UNITED STATES PATENT OFFICE.

HENRY M. VAUGHAN, OF NEWTON, IOWA, ASSIGNOR TO THE WASHBURN & MOEN MANUFACTURING COMPANY, OF WORCESTER, MASSACHUSETTS, AND ISAAC L. ELLWOOD, OF DE KALB, ILLINOIS.

WIRE-BARBING MACHINE.

SPECIFICATION forming part of Letters Patent No. 309,584, dated December 23, 1884.

Application filed April 9, 1883. (No model.)

To all whom it may concern:

Be it known that I, HENRY M. VAUGHAN, of Newton, in the county of Jasper and State of Iowa, have invented a Wire-Barbing Machine, of which the following is a specification.

My object is to form and apply the fence-barb shown and described in the United States Letters Patent No. 212,874, issued to me March 4, 1879, by means of automatic mechanism.

My invention consists, first, in a solid non-rotating shaft to direct and retain two fence-wires relative to each other and a tubular rotating shaft and barb-coiling head; second, in a stationary frame for the barb-cutting mechanism, and the combination of a detachable cutter therewith that can be sharpened by simply grinding its flat surface; third, in the construction and combination of a reciprocating wire-holder with the barb-cutting mechanism; fourth, in a device for holding the parallel wires and bending and tucking the free end of the coiled barb-piece between them; fifth, in wire-moving and barb-spacing mechanism that will advance a coiled barb-piece and partially-finished barb on the parallel wires from the barb-coiler at regular intervals of time and space to the barb-tucking and finishing device; sixth, in a barb-grasping and cable-twisting device that will twist the two parallel wires at regular intervals direct between each two complete barbs as they are successively advanced from the barb-forming to the spooling mechanism in such a manner that each barb will extend at right angles relative to the barbs on its opposite sides; seventh, in a stop-motion gear to impart intermittent partial revolutions to the barb-coiling shaft and head, all as hereinafter fully set forth.

Figure 1 of my accompanying drawings is a side view of my machine. Fig. 2 is an enlarged detail view of a section of my solid non-rotating wire guide and holder. Fig. 3 is a side view showing my barb in two different stages of construction. Fig. 4 shows the barb completed. Fig. 5 is a top view of the machine. Fig. 6 is an enlarged perspective view of my frame for the barb-cutting mechanism to which my detachable cutter is fixed. Fig. 7 is a longitudinal sectional view of the ma-

chine. Fig. 8 is a top view of the driving mechanism. Fig. 9 is a transverse section of Fig. 1, looking to the right from the dotted line marked 9. Figs. 10, 11, 12, 13, and 14 are transverse sections of Fig. 1, looking to the right from the respective dotted lines of corresponding numbers. Fig. 15 shows the lateral-moving wire-holder in contact with the parallel fence-wires, as required to retain them in proper position while the barb is being tucked and finished. Fig. 16 shows the same lateral-moving wire-holder withdrawn from the fence-wires, as required to allow the partially-finished barb to be advanced with the fence-wires. Fig. 17 is a top view of my barb-tucker; and Fig. 18, a perspective view of the end thereof, that is adapted in shape to engage the end of a barb and press it through between the parallel fence-wires.

Jointly considered, these figures clearly illustrate the construction and operation of my complete invention.

A represents the frame and base upon which my various operative devices are mounted. It is preferably one solid iron casting, but may be made in sections and of wood and iron combined.

A² is an extension formed on or fixed to the front end and top of the base A.

A³ is a tubular rotating shaft mounted on top of the extension A² by means of bearings A⁴.

A⁵ is a tubular barb-coiling head screwed upon the rear end of the shaft A³. One side of its free tubular end is cut away, so that the projecting section engages the free end of a barb-piece when it extends at right angles to the head, and to carry it forward in its rotary motion as required to coil the barb-piece around the fence-wire.

A⁶ is my solid non-rotating wire guide and holder.

Heretofore longitudinal bores have been made in a non-rotating guide to direct two wires. I avoid the difficulty of making such bores by forming grooves in the outside surface of the shaft and short inclined bores a a from the end face of the shaft to intersect the grooves in the surface, as clearly shown in Fig. 2.

a' is an elbow and handle at the rear end of the shaft, through which a bore, *a''*, is made to intersect the groove in the under side of the shaft.

5 *a'''* is a catch that engages the handle *a'* when the guide *A⁶* is placed within the tubular shaft *A³*, as required to prevent the guide from rotating. The catch *a'''* is made by simply forming a slot in the edge of the extension *A²*, 10 or by fixing a bifurcated piece thereto.

B (clearly shown in Fig. 6) is the base or frame of my barb-cutting mechanism. It is cast complete in one piece, and has perforated flanges at its ends, through which screw-bolts 15 are passed to fasten it on top of the base *A*.

B' are end pieces or benches that restrict the downward motion of the cutter-carrier operated vertically through the perforations *B²* in said benches.

20 *B³* are inclined faces on the front ends of the benches *B'*. The one inclined face aids in directing the barb-piece as it is projected between the two parallel wires, and both aid in keeping the free end of the barb-piece in proper position relative to the rotating head 25 that coils it around the two wires.

B⁴ is an inclined or triangular projection that extends inward from the front end of one of the benches *B'* to form a bearing and support for the detachable cutter.

30 *B⁵* is a cutter in the form of a flat steel plate fitted to the inside inclined face of the extension *B⁴*, and fixed thereto by means of a screw.

b is an elongated inclined orifice in the cutter, that coincides with a horizontal bore extending diagonally through the bench *B'* and extension *B⁴*, to allow the wire from which the barbs are to be cut to be projected through the orifice *b* of the fixed cutter.

40 *b'* is a perforation through the flat portion of the base of the frame *B*, through which my reciprocating wire-holder *b''* (clearly shown in Fig. 10) is operated.

45 *b'''* are the vertical parts, and *b''''* the cross-pieces, of a frame and cutter-carrier. The vertical parts extend through and move in the perforation *B²* of the base *B* and benches *B'*.

c is a cutter fixed to the under side of the upper cross-bar, *b''''*, in such manner that its 50 lower cutting-edge will engage the barb-wire that projects through the orifice *b* of the fixed cutter *B⁵* as the cutter-carrier descends.

c' is a short square bar that has a screw-shank at its top end to extend through the 55 cross-bar *b''''* of the cutter-carrier and the lower end of the wire-holder *b''*, to be rigidly connected to those parts by means of a nut, *c''*.

c'' is a stud that projects at right angles from the bar *c'* into the continuous groove of 60 a cam-wheel, No. 1, that is fixed to the driving-shaft *C*.

65 *c''''* are straight flat bars bolted to the opposite sides of the bar *c'*, to extend down on the opposite sides of the driving-shaft *C*, to guide the vertical movements of the cutter-carrier that is elevated at every revolution of the cam-wheel No. 1, and also depressed sufficiently at

each revolution by means of an inward bend in the continuous cam-groove in the wheel to operate the cutter as required, to cut off a 70 barb-piece at regular intervals. The wire-holder *b''*, that is carried by the cutter-carrier, is bifurcated at its top end to engage and hold the fence-wires while the barb-piece is being coiled upon the parallel fence-wires before it 75 is cut off.

d is a wire-holder (see Fig. 10) that moves laterally relative to the fence-wires at regular intervals, to allow the incompletely barbs to pass, as clearly shown in the enlarged views, 80 Figs. 15 and 16.

d' is an elbow-crank pivoted to the base *A* and hinged to the stud *c'''* at one end.

d'' is a lever pivoted to the opposite side of the base of the machine.

85 *d'''* is a straight bar hinged to the lower end of the lever *d''* and the lower end of the elbow-crank, as clearly shown in Fig. 10. The top end of the lever *d''* is flexibly connected with the sliding wire-holder *d*, that is in the form 90 of two parallel round bars, *d''''*, connected at their ends by means of angular cross-bars, as clearly shown in Fig. 5.

D is the base-piece of the barb tucking and finishing mechanism, fixed to the base *A* in 95 rear of and in contact with the base-piece *B* of the barb-cutting mechanism. It has horizontal bores, through which the parallel round bars *d''''* pass and move. As the cutter-carrier is depressed by means of the inward bend of the 100 cam-groove in the cam-wheel No. 1, the crank *d'*, connected with the stud *c'''* in that groove, is vibrated to impart motion to the lever *d''*, as required, to withdraw the barb-holder *d* laterally relative to the parallel 105 wires at regular intervals, to allow the incomplete barb to pass as the wires are jointly advanced by the spacing and reeling mechanisms. When a barb-piece is coiled upon the parallel 110 fence-wires, it is advanced to the tucking mechanism to be completed, and the lateral-moving 115 holder *d* moved outward and away from the fence-wires, to allow the incomplete barb to get into a parallel position with the tucker. The holder *d* is then moved inward against 120 the parallel fence-wires, to support them during the operation of the tucker and the completion of the barb. The base-piece *D* has a depressed surface, *D'*, as shown in Fig. 12, upon which the tucker slides.

120 *d''''* (clearly shown in Fig. 7) is a shoulder in the surface *D'*, against which the barb-piece rests while its vertically-projecting end is being pressed into a horizontal position by means of a barb-bender. Before the tucker is operated a barb-bender is required to press the projecting end of the barb-piece into parallel 125 position with the parallel wires, as shown at the right in Fig. 3.

e is a barb-bender fixed to the end of a rock-shaft, *e'*, that projects through a bore and bearing formed in the base *D*, as clearly shown in Figs. 1, 5, and 12.

e'' is a crank on the end of the shaft *e'*.

e''' is a bridle in the crank e'' .

e''' is a reciprocating bar that is bifurcated at its top end and connected with the bridle of the crank e'' by means of a bolt. It has a 5 bridle, e'''' , extending at right angles from its bottom end, through which a crank-pin, f , extends from the side face of a rotating disk, f' , in such a manner that the rotary motion of the disk will impart reciprocating motion 10 to the bar e''' and rock the shaft e' at regular intervals, as required, to operate the barb-bender e , and to thereby bend the barb that projects vertically, as shown at the left end of Fig. 3, into a horizontal position and parallel 15 with the parallel wires, as shown at the right end of the same figure, preliminary to tucking it through between the fence-wires and into position, as shown in Fig. 4.

To hold the parallel wires firm while the 20 barb is being tucked and completed, I provide a wire-holding device in rear of the tucking device.

D^2 is the frame and bearing of this auxiliary wire-holder, fixed on top of the base A and 25 against the rear side of the base-piece D, as clearly shown in Figs. 1, 7, and 11.

b'''' is a reciprocating wire-holder, constructed as clearly shown in Fig. 11, and operated by means of the cam-wheel No. 2, fixed to the 30 driving-shaft C in such a manner that it will retain the parallel wires in the vertical slot (that intersects an orifice at its top) while the barb is being tucked and completed, and then ascend to allow the complete barb to pass 35 through the orifice as the parallel wires are advanced in the machine.

f'' is my sliding barb-tucker. It has a longitudinal slot, f''' , that is curved laterally at its rear end. It is attached to the depressed 40 top surface, D' , of the base-piece D by means of screw-bolts f'''' , that extend through the slot of the tucker into the base, and serve as guides in directing the movements of the tucker through between the parallel wires, 45 and then, by means of the curve in it, laterally to bend the barb away from the wires.

f^5 is a pointed projection formed on or fixed to the front end of the sliding tucker f'' , to pass between the parallel fence-wires in advance 50 of the square and grooved end of the tucker, to separate the fence wires sufficiently for the passage of the tucker and the end of the barb carried thereby. The body of the tucker is flat, and its front end adapted in 55 shape to engage the end of a barb and carry it through between the parallel fence-wires and press it into position, as shown in Fig. 4.

g is a handle fixed to the tucker to extend laterally. This handle is flexibly connected with 60 a lever, g' , by means of a link, g'' , that is bifurcated at its ends, as clearly shown in Fig. 12. The lever g' extends down through an opening 65 in the base A, and is supported by means of a fulcrum, g''' , fixed to the base. It has a bridle, g'''' , in its lower end, through which the pin of a crank, g''''' , extends in such a manner that the revolving motion of the crank

will vibrate the lever as required to operate the tucker at regular intervals.

F is a shaft suspended across the under side 70 of the base A by means of hangers, as clearly shown in Figs. 1 and 13.

F' is a lantern-wheel in form, fixed to the middle of the shaft, to aid in advancing the parallel wires at intervals as required, to fix 75 the barbs thereon at regular intervals of time and space. This wheel extends up through an opening in the base A to a level with the parallel wires, that are passed around it and advanced at regular intervals relative to the 80 barb-cutting and barb bending and tucking devices by the intermittent rotary motions of the wheel F' .

No. 3 is a wheel fixed to the shaft F to perform the function of a ratchet-wheel. 85

F^2 is a pawl-bearer hinged to the shaft F at its top end and connected with a grooved cam-wheel, F^3 , that is fixed to the driving-shaft C. The wheel No. 3 has a continuous groove in its side face, as indicated by dotted lines in 90 Fig. 1, into which the pawl h , pivoted to and carried by the bearer F^2 , is projected in such a manner that it will clamp fast in the continuous groove of the wheel No. 3 in a forward motion of the arm or bearer F^2 and slide 95 therein in a reverse or backward motion, as required, to impart intermittent motions to the wheel F' and advance the parallel wires regular distances corresponding with the spaces between the barbs fixed thereto as the 100 wires are jointly moved through the machine from coils supported at the front end to a reel at the rear end.

No. 4 is a ratchet-wheel fixed to the opposite end of the shaft F from the wheel No. 3. 105

h' is a gravitating pawl pivoted on top of the base A, to engage the wheel No. 4 and to prevent any backward motion of the wire-moving wheel F' and relapse of the parallel wires to which the barbs are fixed. 110

No. 5 is a ratchet-wheel fixed to the shaft F.

F^4 is a pawl hinged to a post rising from the base A in such a manner that a stud on its lower end will enter a continuous groove in the wheel F^3 and allow the shoulder in the side 115 of the pawl to engage one of the teeth of the wheel No. 5 at each revolution of the shaft C, to restrict the advance of the parallel wires to equal distances at each motion of the wheel No. 3. 120

G is a barb-grasping and cable-holding device fixed on top of the base A in line with the advancing barbed cable-wires. It has a concave mouth to direct the projecting barbs into a longitudinal slot therein, through which 125 the barbs can slide, but in which slot the barbs and complete cable will be prevented from revolving.

G^2 is a tubular shaft mounted at its front end upon the base A in line with the barb-grasping device G. It also has a concave mouth and a cruciform longitudinal passage-way for the barbed cable, that will grasp barbs on the cable and twist it as the shaft is re- 130

volved, and make one or more twists in the cable at the point intervening between the parts G and G² every time a barb is completed and the parallel barbed wires advanced a distance corresponding with the uniform spaces between the barbs.

H is a driver chain-wheel fixed to the rotating shaft and twister G².

H² is a driver chain-wheel fixed to the rear end of the driving-shaft C.

I is a drive-chain placed upon the chain-wheels, to transmit power and motion from the shaft C to the shaft G² to operate the twister slowly and continuously.

To secure the intermittent motions required to wrap the barb-pieces around the two parallel wires, I employ a stop-motion gear, which consists in a wheel having a series of cogs upon its periphery at distances apart and depressions at the end of each series, as clearly shown in Fig. 9, and one or more pairs of long cogs in a pinion, to slide on the smooth portion of the periphery and retain the pinion stationary until one of the long cogs enters one of the depressions, to allow the pinion to revolve until the ends of a pair of the long cogs again both engage a smooth section of the periphery of the continuously-revolving mutilated gear.

No. 6 is a mutilated-gear wheel having four distinct series of cogs and depressions, i, on each side of each series, as required to impart four distinct motions to the pinion J, that has two pairs of long cogs, k k, at each revolution of the wheel No. 6, fixed to the front end of the shaft C.

No. 7 is a stop-motion gear-wheel fixed to the shaft C, to operate my barb-bender and barb-tucker mechanisms. It has only one series of teeth to engage a pinion, L, that has only one pair of long cogs, and is fixed to a shaft, L², suspended in hangers from the under side of the base A in such a position relative to the wheel No. 7 and the bar e''' that motion will be imparted to the shaft L² to rotate the disk f', and thereby operate the barb-bender e at each revolution of the shaft C.

L³ is a pinion having a pair of long cogs fixed to a suspended shaft, L⁴, in such a position relative to the wheel No. 7 and the lever g' that a crank, m, fixed to the shaft L⁴, will engage and vibrate that lever at every revolution of the shaft C, as required to actuate the tucker f" at regular intervals.

No. 8 is a stop-motion gear-wheel fixed to the shaft C, to operate mechanism for advancing the barb-wire to the cutting mechanism at regular intervals.

n n are feed-wheels. (Shown in Fig. 5.)

o is a shaft suspended in hangers from the base A, to operate the feed-wheels n by means of bevel-gear wheels (shown in dotted lines in Fig. 1 and in full in Fig. 8) in a common way. A pinion, o', having one pair of long cogs on the end of the shaft o, engages the wheel No. 8, to be actuated thereby, as required to transmit intermittent motions to the feed-wheels at regular intervals.

No. 9 is a driver-pulley fixed to the shaft C, to receive a belt connected with a motor adapted to operate my machine.

From the foregoing detailed description of the construction and function of each element and sub-combination of my machine, the unitary action of all the moving parts and the practical operation of my complete invention will be obvious to persons familiar with the construction and operation of wire-barbing machinery.

I claim as my invention—

1. In a wire-barbing and cable-forming machine, a solid non-rotating shaft having longitudinal grooves in its surface and short inclined bores at its rear end intersecting said grooves, in combination with a rotating tubular shaft carrying a barb-coiling head, substantially as and for the purposes set forth.

2. The detachable shaft A⁶, having grooves in its surface to admit wires, and inclined bores a a at its rear end, in combination with the tubular rotating shaft A³ and a catch, a'', fixed to the base, substantially as shown and described, for the purposes specified.

3. The base-piece B, having benches B', perforations B², inclined faces B³, and a tapering projection, B⁴, in combination with barb-cutting mechanism supported thereby, substantially as shown and described.

4. The detachable flat cutter B⁵, having an inclined orifice, b, in its central portion, in combination with the base B, having a tapering extension, B⁴, and a bore coinciding with the orifice in the cutter, substantially as and for the purposes set forth.

5. The reciprocating wire-holder b'', in combination with the base B, having a perforation, b', the reciprocating cutter-carrier b''' b''', the cutter c, the shaft A³, carrying a barb-coiling head, and the non-rotating wire guide and holder A⁶, substantially as and for the purposes set forth.

6. The reciprocating cutter-carrier composed of the parts b'' and b''', the cutter c, the base B B', having perforations B², and an extension, B⁴, and the fixed cutter B⁵, arranged and combined substantially as shown and described, and for the purposes specified.

7. The combination of the lateral-moving wire-holder d, the fixed base D, the elbow-crank d', the cam-wheel No. 1, the lever d'', and the bar d''', substantially as and for the purposes shown and described.

8. The barb-bender e on the rock-shaft e', in combination with the base-piece D, having a depressed surface, D', and a central passage-way for parallel barbed wires, substantially as and for the purposes set forth.

9. The base D D', the barb-bender e e', the crank e'', having a bridle, e''', the reciprocating bar e''', having a bridle, e''''', and a rotating disk having a crank-pin, f, arranged and combined substantially as shown and described, for the purposes set forth.

10. The frame D², the reciprocating auxiliary wire-holder b''', having an opening through

which the wires pass, and a slot extending upward from said opening, and also having a bifurcated lower end to stride a shaft, and a stud to engage the grooved cam-wheel No. 2, 5 substantially as shown and described, for the purposes specified.

11. The sliding barb-tucker f'' , having a slot, f''' , in combination with the base D D', substantially as and for the purpose set forth.

10 12. The base D D', the sliding tucker $f'' f'''$, having a handle, g , the lever g' , having a bridle in its long arm, and a revolving crank having a pin to engage the bridle in said lever, substantially as and for the purposes specified.

15 13. The combination of a barb-bender arranged to move longitudinally relative to two parallel wires, as required, to bend a projecting barb into line with them, and a tucker arranged to move at right angles relative to the 20 parallel wires, as required, to push a barb through between the parallel wires.

25 14. The wire-moving and barb-spacing mechanism, consisting of the shaft F, the wheel F', the wheel No. 3, having a continuous groove in its side face, the hinged pawl-bearer F², carrying a spring-pawl, h, the ratchet-wheel No. 4, the gravitating pawl h', the ratchet-wheel No. 5, the hinged pawl F¹, having a shoulder in its side and center and a 30 stud at its lower end, and the driving-shaft C, having a fixed grooved cam-wheel, F³, substantially as shown and described.

35 15. The barb-grasping device G, having a concave mouth and a longitudinal slot, in combination with a wire-barbing machine to restrict barbed wires from twisting while advancing, substantially as set forth.

40 16. The barbed-wire-twisting and cable-forming device, consisting of the fixed grasping device G, having a concave mouth and

longitudinal slot, and a rotating tubular shaft, G², having a concave mouth and a longitudinal cruciform passage-way, substantially as shown and described.

17. The combination of barb-forming and 45 barb-applying mechanism, wire-moving and barb-spacing mechanism, a barb, and cable-grasping device G, having a concave mouth and a longitudinal slot, and a rotating cable-twisting device, G², having a concave mouth and a 50 longitudinal cruciform passage, for the purposes set forth.

18. A stop-motion gear consisting of a wheel having one or more series of uniform cogs on its periphery and depressions at the ends 55 of each series of cogs, and a smooth surface between such depressions, and a pinion having one or more pairs of long cogs adapted to enter the depressions at the ends of each series of cogs in said wheel, and to slide upon the 60 smooth sections intervening between such depressions at the ends of the series of cogs, in combination with a rotating shaft carrying a barb-coiling head, substantially as shown and described, for the purposes specified. 65

19. The lateral-moving wire-holder d, a fixed base, and suitable operating mechanism, in combination with barb-tucking mechanism, as required, to retain parallel wires stationary while the barb-pieces are tucked. 70

20. The barb-bender e e', in combination with a suitable base and operative mechanism for the purpose of bending a barb from a right-angled position relative to two parallel wires to a parallel position with said wires, for the 75 purposes set forth.

HENRY M. VAUGHAN.
